UNITED STATES PATENT OFFICE.

GEORGE H. FAICHNEY, OF WATERTOWN, NEW YORK, ASSIGNOR TO THE RANDALL-FAICHNEY COMPANY, OF BOSTON, MASSACHUSETTS, A CORPORATION OF MASSACHUSETTS.

MULTIPLE-ENGRAVING MACHINE.

1,359,240.

Specification of Letters Patent. Patented Nov. 16, 1920.

Application filed January 2, 1920. Serial No. 349,113.

To all whom it may concern:

Be it known that I, GEORGE H. FAICHNEY, a citizen of the United States, residing at Watertown, in the county of Jefferson and 5 State of New York, have invented certain new and useful Improvements in Multiple-Engraving Machines, of which the following is a specification.

This invention relates to improvements in 10 engraving machines, particularly of the type employed for inscribing names, numbers and the like upon stock articles.

The object of the invention is to provide a machine of the class, which is controlled 15 and actuated by a pantograph mechanism, and which is arranged to engrave a large number of articles at the same time, by the employment of a single operator. A further object is to provide a multiple engraver, 20 which is arranged for simultaneously engraving articles of different size and shape, without requiring any special adjustment, or alteration or change of any of the parts of the device, and wherein the graving or 25 scribing may be effected on flat, concave or convex surfaces by means of self-adjusting gravitational engravers, which may be simultaneously thrown into the operative or released positions by the operator. A further 30 object is to provide a frame for supporting the engravers and related parts, which is adapted for universal movements in a horizontal plane, by a single connection with the pantograph mechanism. And a further 35 object is to provide a normally stationary work-supporting table, and novel and simple means for adjusting the said table.

I attain these objects by the means set forth in the detailed description which follows, and as illustrated by the accompanying 40 drawings, in which—

Figure 1 is a top plan view of the complete machine, showing a pantograph operatively connected thereto. Fig. 2 is a rear side elevation of the same. Fig. 3 is a rear end elevation of the machine. Fig. 4 is an enlarged sectional view, taken substantially on line 4—4 of Fig. 2; showing the construction, arrangement and operation of one 45 of the gravitational engravers. Fig. 5 is an enlarged detail view of the means for simultaneously raising and lowering the engravers, taken in the direction of the arrow in Fig. 2. Fig. 6 is a broken plan view of 50 the removable work supporting table. Fig. 55 7 is a cross section, taken on line 7—7 of Fig. 6; showing the grooves which receive and support the work. Fig. 8 is a vertical longitudinal section taken on line 8—8 of Fig. 6; showing the means for adjusting 60 the work table.

In the drawings, 2 is the base which supports the entire mechanism, upon which is mounted a stationary frame, which comprises upright posts 3 and 3', and rabbeted 65 bars 3^a and 3^e, the latter extending transversely and parallel across the base, and being rigidly secured to the corresponding posts by screws 3^d. The bars 3^a and 3^e are spaced apart and their rabbeted edges face 70 each other and slidably receive a false platform or table 3^e, which is normally stationary during the engraving operations, but may be adjusted along said bars by screws 3^f. 4 represents the removable work supporting table, which is slidable longitudinally, for positioning the work relatively 75 to the engraving tools or needles, on the platform 3^e, between cleats 3^x, as shown by dotted lines in Figs. 1, 2 and 8. The table 80 4 is adjusted by means of a lever 4', which is pivoted at one end to the rear underside of the platform 3^e, the other end of said lever projects beyond the front edge of the platform within reach of the operator. Between its ends, the lever 4' is provided with an upwardly facing socket 4^a, which receives a stud 4^b carried by the table 4, the said socket being positioned in a slot 4^c in the platform 3^e, which permits the table 4 to be moved in opposite directions by the 85 corresponding movements of said lever (see dotted lines in Figs. 1 and 8). The top side of the table 4 has a plurality of parallel longitudinal grooves 4^d, 90 which receive and hold the work C during the engraving operations. Two or more of the work tables 4 are usually provided for each machine, and they are readily and quickly detached from the platform, by 100 simply disconnecting the studs 4^b from the socket 4^a. By this arrangement, while the work carried by one table is being engraved, the other tables may be unloaded and re-loaded, thus permitting the machines to be 105 operated continuously.

The present machine has been designed particularly for engraving the trade-name

and place of manufacture on thermometers, but it is obvious that the same mechanism may be employed for engraving various other articles without materially changing the construction and arrangement of the parts. Heretofore, the engraving of thermometers has been done by machines of the pantographic type, which were arranged for engraving but one thermometer at a time. This required a large number of machines and an operator for each machine, which rendered the work slow and tedious, and also quite expensive. Besides, these single engravers required careful and accurate adjustment of the engraving needles for work of different sizes and shapes in order to obtain the proper pressure of the tools upon, and for the exact positioning of the needles relatively to the work. Careless and inexperienced operators therefore often turned out work which was imperfect, and frequently the more or less fragile articles were broken, due to faulty adjustment, or excessive weight or pressure of certain of the working parts. It is a particular object of the present invention to provide a plurality of similar engraving tools which perform identical work. These tools are all self-adjusting and operate simultaneously. When the engraving operation is about to begin, the engraving tools are all released and instantly gravitate to the operative position, in contact with the work. No adjustment of the tools is required, because the weight of said tools is so proportioned as to effect the requisite pressure for performing uniform and perfect work without any attention or assistance from the operator.

The engravers herein shown and described consist of suitable sharp pointed needles or tools 5, which are detachably inserted in the lower ends of plungers or stocks 6, the latter being reciprocally held and truly guided vertically by brackets 6', the said brackets having their horizontal arms slotted for adjustably securing them to similar supporting bars 7 and 7', by bolts 6". The bars 7 and 7' are arranged in pairs and are preferably disposed parallel and are spaced apart to properly support and steady the brackets 6'. As shown in Figs. 2 and 3, the brackets 6' are alternately reversed and bolted on each pair of bars 7 and 7', which serves to properly balance the parts, and at the same time permits the employment of a large number of engravers within a relatively small space. The bars 7 and 7' are longitudinally disposed in the machine and are supported at their opposite ends by cross-bars 8, which are rigid on posts 8', the latter being supported by transverse cleats 9' which are mounted near the opposite ends of a platform 9. The platform 9 and all of the parts mounted upon it are movable transversely and longitudinally as one part

and they are also permitted suitable circular movements in the same horizontal plane, by means of a plurality of ball bearings 10 and 11. The bearings 10 consist of elongated grooved members 10' which are rigidly secured to the underside of the platform 9, and similar members 10" which are rigidly mounted on the topmost members 11' of the second series of bearings. 11" represents the lowermost members or races 75 of the second bearings, which are rigidly secured to the stationary base 2 and are preferably spaced therefrom by posts 9". 10" and 11" represent respectively the balls for the two sets of bearings. By the provision of the ball bearings 10 and 11, the engravers 5, as well as all the other parts carried by the platform 9, may be given practically universal movement in a horizontal plane for engraving straight lines or 80 curves, as indicated by the dotted lines in Figs. 1, 2 and 3. When the platform 9 is moved forward and backward, the members 10' of the bearings 10 alone move, while all the other bearing members below them remain stationary. When the platform 9 moves longitudinally, all of the bearing members except the lowermost members 11" move with the platform as one part.

The work supporting table 4 is shown 95 loaded with (clinic) thermometers C, there being one thermometer for each of the engravers 5. When the machine is idle, the plungers 6 are held in the released position 100 a suitable distance above the work, by a plurality of rocking bars 12, the opposite ends of which are journaled in transverse rails 12' which are mounted on posts 12", the latter being supported by the cross-bars 8, all of which move with the platform 9. The 105 rocking bars 12 have V-shaped top edges upon which rest horizontally disposed fingers 6", the latter being rigidly connected to the top ends of the plunger 6. When the bars 12 are in their normal position (see full 110 lines in Figs. 2, 4 and 5) they hold all of the needles above and clear of the work on the table 4. The rocking bars 12 are operated by the following means; 12" designates similar wheels which are rigid on the 115 corresponding ends of the bars 12. These wheels are tied together for simultaneous operation by a rod 12". One of the wheels 12" is provided with an arm 12' to which a cord 12" is attached and passes downwardly 120 through the platform 9 of the base 2 and connects with a pedal (not shown) on the floor. When the operator is ready to start the engraving work, she depresses the pedal, which pulls downwardly on the cord 12" 125 and partially turns all of the rocking bars, from the full and dotted line positions, as best seen in Figs. 4 and 5. This simultaneously releases all of the plungers 6 and allows the needles 5 to gravitate toward the 130

work C. The arrangement of the rocking bars 12 (see dotted lines in Fig. 4) is such that the needles 5 and the plungers 6 are free to exert their full weight on the work 5 C during the engraving operations, and in practice the weight of these parts is varied to suit different kinds of work. During the engraving operation the operator keeps her foot on the pedal, while she traces with the 10 point 15' the words and other matter comprising the copy A, which is conveniently mounted in a grooved holder 15° secured to the front portion of the base 2. When the engraving of the parts C is finished the operator releases the pedal and a spring S attached to the rod 12° rocks the bars 12 in the opposite direction, which lifts all of the needles 5 away from the work, (see full lines in Figs. 2, 3 and 4), and holds them there 15 ready for the next operation.

The engraving mechanism, and all of the parts mounted upon the oscillating platform 9, except the gravitation and release of the engravers 5, is controlled and actuated by 20 a pantographic mechanism of well-known type, which consists of a standard 13, having a forked arm 13', in which is pivoted a lever 13^a at 13^b. To the lever 13^a is pivoted a lever 13^c at 13^d. The lever 13^c is also pivotally connected to the platform 9 by a post 30 14. As the axis of the post 14 is eccentric to the pivot 13^d, by the swinging, in a horizontal plane, of the lever 13^c, the platform 9 and all of the parts carried by it are given 35 the various horizontal movements, as described. One end of the lever 13^a is pivoted to a tracer arm 15, the forward end of said arm being fitted with a tracer point 15', which the operator guides over the copy (A) 40 of the matter to be engraved on the work C. The opposite end of the arm 15 is tied to the rear end of the lever 13^c by a rod 16. By adjusting the several levers 13^a, 13^c, and the arm 15, in a well-known manner, the operator 45 is able to re-produce the words, letters and figures of the copy A, on either a reduced or enlarged scale upon the work C. The full and dotted lines in Figs. 1 and 3 show the range of movement of the tracer 50 arm 15 and the other parts of the pantograph for effecting the corresponding movements of the platform 9 and the needles 5 while engraving the work C. The re-production herein shown is on a reduced scale.

55 The plungers 6 are free to rotate in the brackets 6', to the extent shown by the different positions of the fingers 6^b in Fig. 1. To prevent the fingers from becoming accidentally detached from the rocking bars 12, their free ends are bent downwardly as shown in Fig. 4.

In case an engraving needle becomes broken or injured, or a smaller number of articles are to be engraved than the machine 60 is arranged for, the operator may readily

and quickly withdraw one or more of the needles, by simply lifting them out of the brackets 6, where they are held by gravity, and insert new needles, or else proceed with the engraving with fewer of the needles. 70

The present machine is arranged to engrave twenty-five articles at one operation, and obviously this number may be increased or diminished at will. The table 4 with its grooves for holding the work C, is particularly adapted for engraving the trade-mark and similar matter, which need not be positioned relatively to the graduations on the thermometers with the same precision as is required for the degree numbers, and therefore it is not necessary for the operator to watch the work closely during its progress. 75

Having thus described my invention, what I claim, is—

1. In a multiple engraving machine, a plurality of gravitational engraving tools, adapted to effect engraving by their own weight, a support for said tools, said support adapted for holding the points of all of said tools in a horizontal plane when the tools are idle, means for lowering said tools toward the work, and means for simultaneously moving all of said tools in a horizontal plane during the engraving operations. 90

2. In a multiple engraving machine, a plurality of gravitational engraving tools adapted to perform identical work simultaneously, a support for said tools, means for actuating said support for moving all 100 of said tools in a horizontal plane, a work-supporting table disposed beneath said tools, means for effecting the gravitation of said tools toward the work on said table, and means for guiding said tools during their 105 vertical movements.

3. In a multiple engraving machine, a plurality of engraving tools adapted to perform identical work simultaneously and to be held in engraving contact with the work 110 by gravity, an adjustable support for each engraving tool which serves to truly guide the tool in its movements toward and away from the work, a frame for supporting all of said tools adapted for universal movements in a horizontal plane, means for actuating said frame, and a table adapted to hold the work stationary during the engraving operations. 115

4. In a multiple engraver, the combination with a pantograph mechanism, of a movable platform, a post carried by said platform pivoted to a part of said mechanism whereby said platform is moved forwardly, backwardly and circularly in a horizontal plane, a work-supporting table disposed above said platform, a plurality of gravitational engraving needles supported by said platform above said table and movable horizontally by said platform, and rocking- 125 130

- bars controlling the vertical movements of said needles toward and from said table.
5. In a multiple engraving machine, a frame movable in a horizontal plane, a work-supporting table, means for adjusting said table, a plurality of gravitational engraving tools movable with said frame and adapted for vertical movements toward and away from said table independent of said frame,
- 10 means for actuating said frame for effecting said horizontal movements, means for preventing the vertical movement of said tools, and means for moving said tools into engraving contact with work disposed on said table.
- 15 6. In a multiple engraving machine, a stationary work-supporting table, a platform adapted for universal movements in a horizontal plane, means for operating said platform, a plurality of gravitational engraving tools carried by said platform and positioned above said table, means for raising and holding said tools out of engagement with work on said table, means for simultaneously releasing all of said tools for allowing them to gravitate into engraving contact with the work, and means for maintaining the axes of said tools in a truly vertical plane.
- 20 25 7. In a multiple engraving machine, a platform adapted for universal movements in a horizontal plane, means for actuating said platform, a work-supporting table adjustably mounted above said platform and normally stationary during the engraving operations, rocking bars disposed above said table, said bars supported by and movable with said platform, engraving needles having fingers resting on said bars, adapted to
- 30 35 40 45 50 55 60 65 70 75 80 85 90 95 100 105 110 115 120 125 130 gravitate toward said table and to be lifted away from the table by the rocking of said bars, and means for adjusting said table for positioning the work relatively to said needles.
8. In a multiple engraver, a frame movable in a horizontal plane, a work-supporting table adjustable longitudinally, a support for said table adjustable transversely in said frame but not connected to said frame, a plurality of engraving tools supported by and movable with said frame, said tools positioned above said table and adapted for vertical movements independent of the frame, tension controlled means for holding said tools out of engagement with work disposed on said table, and means for overcoming said tension for allowing said tools to gravitate into engraving contact with the work on said table.
9. In multiple engraving machines, the combination with a pantographic mechanism, a horizontally movable platform operatively connected to said mechanism, a work-supporting table adapted to be held stationary during the operation of said plat-
- form, a plurality of similar engraving tools supported by and movable with said platform adapted for vertical movement independent of the platform, tension controlled rocking-bars for lifting and holding said tools away from the work on said table, and means for rocking said bars against the tension for allowing said tools to gravitate into engraving contact with the work.
10. In a multiple engraving machine, a platform movable solely in a horizontal plane, a work-supporting table adjustably mounted above said platform, a plurality of engraving needles supported by said platform and movable horizontally therewith, brackets for holding and guiding said needles in a true vertical plane when said needles move toward and away from said table, said needles being free to rotate for preventing the uneven wearing of their points, means for lowering said needles to the engraving position, and means for lifting and holding said needles away from the work.
11. In a multiple engraving machine, the combination with a pantograph mechanism having a tracer arm adapted for tracing the copy of the matter to be engraved, of a platform adapted for universal movements in a horizontal plane, a post carried by said platform pivoted to a part of said pantograph, a stationary frame, a work-supporting table adjustably mounted on said frame, a plurality of gravitational engraving needles supported by said platform and movable in a horizontal plane therewith, said needles adapted to move vertically toward and away from said table, and a plurality of rocking bars for controlling the vertical movements of said needles.
12. In a multiple engraving machine, a stationary frame, an adjustable work-supporting table mounted on said frame, a platform disposed beneath said table and movable in different directions in a horizontal plane, a plurality of engraving needles carried by said platform and movable therewith in a horizontal plane, said needles arranged in rows and disposed above and substantially in registry with the work on said table, rocking bars for holding said needles away from the work, and means for rocking said bars for allowing all of said needles to gravitate toward the work.
13. In a multiple engraving machine, a platform adapted for universal movements in a horizontal plane, means for actuating said platform, a stationary frame above said platform, a work-supporting table adjustable on said frame having parallel grooves for holding the work to be engraved, rocking bars disposed above and parallel to said grooves, said bars supported by and movable with said platform, engraving tools having fingers resting on said bars, said tools arranged in rows corresponding to and

spaced above said grooves and adapted to gravitate toward the work when the operator rocks said bars in one direction, said tools adapted to be lifted away from the 5 work by the automatic rocking of said bars in the opposite direction.

14. In a multiple engraving machine, a stationary work-supporting table, a platform adapted for movements in a horizontal 10 plane, means for actuating said platform, a plurality of gravitational engraving tools carried by said platform and disposed above said table, means for holding said tools out of engagement with the work on said table, 15 and means for simultaneously releasing all of said tools for allowing them to gravitate into engraving contact with the work.

15. In a multiple engraving machine, the combination with a pantograph mechanism, 20 having a manipulatable tracing arm, of a horizontally movable platform operatively connected to said mechanism, ball-bearings on which said platform moves longitudinally, ball-bearings on which said platform 25 moves transversely, a plurality of gravitational engraving tools supported by and movable with said platform, a normally stationary work-supporting table disposed between said platform and said tools, said table having work receiving grooves arranged to face and register with said tools, brackets for 30 guiding said tools when they move vertically, bars arranged in pairs for supporting said brackets, said bars being rigid on and 35 movable with said platform, rocking-arms supported by said platform above the other bars, said rocking-bars arranged to automatically lift and hold said tools out of engagement with the work on said table, and 40 means for rotating said rocking-bars for allowing all of said tools to gravitate into engraving contact with the work on said table.

16. A multiple engraving machine, includ- 45 ing a stationary frame, a work supporting table adjustably mounted on said frame, a platform disposed beneath and parallel to

said table, a plurality of ball-bearings arranged in pairs disposed beneath and supporting said platform, one pair of said bearings disposed transversely, the other pair of said bearings disposed longitudinally relatively to said platform, a plurality of engraving tools supported by said platform above said table, a bracket in which each tool 50 is vertically reciprocable and freely rotatable, parallel bars on which said brackets are reversely and adjustably mounted supported by said platform, rocking-bars adapted for normally holding said tools a uniform 55 distance from the work on said table, means for rotating said rocking-bars for allowing said tools to gravitate into engraving contact with work supported by said table, and means for simultaneously moving all of said 60 tools away from the said table, for permitting the removal of the work.

17. In a multiple engraving machine, a base, a pair of ball-bearings mounted on said base, one member thereof rigid on said 70 base, a pair of ball bearings mounted on the first pair and at right angles thereto, the lowermost members of the second bearings rigid to the topmost members of the first bearings, a platform rigidly secured to the 75 topmost members of the second bearings, a stationary work-supporting table disposed above said platform, a plurality of gravitational engraving needles positioned above said table and adapted for vertical move- 80 ments toward and away from the work on said table, brackets for supporting and guiding said needles, rocking-bars controlling the vertical movements of said needles, means for rocking said bars for raising said 85 needles, means for rocking said bars for allowing the gravitation of said needles, and means for moving said platform on said bearings in different directions horizontally and for correspondingly moving all of said 90 needles.

In testimony whereof I affix my signature.

GEORGE H. FAICHNEY.
